Application March 3, 1936, Serial No. 66,830
In Great Britain March 8, 1935

8 Claims. (Cl. 112—62)

This invention is concerned with improvements in or relating to sewing machines, and is particularly, but by no means exclusively, concerned with machines which are arranged for sewing together parts of suitcases, attaché cases, camera cases or the like by a lockstitch seam.

Machines of a known type for sewing together the parts of attaché cases or the like frequently have an external work-support presenting two work-supporting faces extending at right angles to each other to support the two parts to be sewn together (one of said faces for example extending forwardly and upwardly at about forty five degrees to the horizontal and the other extending forwardly and downwardly at the same angle) and a depending work-entering horn which is arranged to press the two parts of the work against the faces of the work-support, the horn having a bowed shape and presenting at its lower end a work-entering portion which extends rearwardly and downwardly towards the junction of the two faces of the work-support and being arranged for lateral swinging movement, during the work-engaging portion of the horn and extends upwardly at a substantial angle to both of the faces of the work-support, e. g. the said axis lying perpendicularly to a line bisecting the angle between the faces when the machine is looked at from the side i. e. along the line of work feed.

Horns of this kind mounted in the manner indicated have proved able in practice to support and control adequately work of various kinds to allow the parts to be sewn firmly together but nevertheless the relation above indicated, to the work-supporting faces of the work support, of the work-entering portions of such horns and the fact that the horns are mounted to swing about axes which extend at a substantial angle to the two faces of the work-support occasionally present difficulties in the sewing together of parts of cases which have but small mouths, particularly cases, such as camera cases and music cases, which are relatively deep and relatively narrow from front to rear. This is largely because the swinging movements of the horn which are necessary, in sewing a side into a case, to allow the sewing to progress from the open mouth along one side corner of the case, around the closed end thereof and along the other side corner towards the open mouth tend to cause the work-entering portion of the horn, in its swinging movements to strike against the front wall of a relatively narrow case and prevent the continuance of the sewing together of the two parts to be joined.

One of the several objects of the present in-

vention is to overcome this disadvantage by providing a horn which will give efficient control of the work and can enter readily into a narrow case and, in spite of the fact that it may be swung from side to side as required during the sewing operation, will not cause the portion thereof of extending into the case to move in such a manner as to obstruct the completion of the sewing operation on the case.

In a particular illustrative embodiment of the present invention hereinafter more particularly described a rotary horn is mounted to swing laterally about an axis which, instead of extending at a substantial angle to both the faces of the work-support, is arranged parallel, or at least almost parallel, to the lower downwardly and forwardly extending face of the external support (i. e. is arranged at an angle extending upwardly and rearwardly, at about forty-five degrees to the horizontal) and the work-entering portion of the horn is bowed at such an angle to its main portion that it lies perpendicularly to the axis just mentioned, that is, it lies parallel, or almost parallel to the upwardly and forwardly sloping face of the external support. The said work-entering portion is spaced far enough forwardly of this face of the support as to allow the mounting on it, coaxially with said axis, of a substantially cylindrical work-engaging roll, the peripheral and rearward end faces of which are arranged to press the two parts to be sewn together against the respective faces of the work-support.

By arranging for the horn to swing about an axis inclined as above indicated, it will be appreciated that the horn may be swung through one hundred and eighty degrees from a position extending towards the left into a position extending towards the right without causing its work-entering portion to deviate out of its parallelism with the forwardly and upwardly extending face of the work support and without moving to any measurable extent forwardly or rearwardly away from or towards the latter. Therefore, the horn will offer effective support to the work, through the said roll, in all positions to which it may be swung and will not strike against the forward or rearward side of the work during its swinging movement. Moreover, by arranging for the work-entering portion of the horn always to occupy such a parallel relation to the upwardly extending face of the work-support, cases or the like which are but just wide enough at the mouth to allow the horn to enter into them can be sewn by the machine since the work-entering

portion of the horn will not move forwardly or rearwardly, at least to any measurable extent, in the case and will not therefore be likely to strike against its forward or rearward sides.

In order that the various objects and the several features of the present invention (which latter are hereinafter set forth in the appended claims) may be more clearly understood, the illustrative embodiment aforementioned will now 10 be described with reference to the accompanying drawings.

In the drawings:

Figure 1 is a right hand side elevation of the head of a machine including the said illustrative embodiment;

Figure 2 is a view similar to Figure 1 on a somewhat larger scale;

Figure 3 is a plan view of certain parts of the machine;

Figure 4 is a detail view on the line 4—4 of Figure 3;

Figure 5 is a detail sectional view on the line 5—5 of Figure 2; and

Figure 6 is a detail sectional view of certain 25 of the parts for supporting the horn of the machine.

The machine illustrated in the drawings is of the type disclosed in the specifications of British Letters Patent Nos. 430,984 and 415,480, 30 corresponding respectively to U. S. application of Gouldbourn and Kestell No. 749,594, filed October 23, 1934, and U. S. patent to Gouldbourn No. 2,029,099, dated January 28, 1936. Like the machine disclosed in said patents and application, 35 the illustrated machine has an external work support with angularly disposed work engaging surfaces, a bag entering horn provided with a work support to engage the work internally, a horn actuating and controlling mechanism, and 40 means for effecting conjoint angular adjustment of the horn and external work support.

The illustrated machine may be provided with a horn constructed and arranged as in U. S. patent to Gouldbourn above referred to. Such 45 a horn is indicated in dot-and-dash lines at 3 in Figures 1 and 2, being mounted in a horn supporting mechanism which is similar in all respects to that disclosed in the Gouldbourn patent. This horn supporting mechanism is detachably secured by two vertical bolts, one of which is indicated at 9, to a block 4 mounted upon pivot pins 7 at the forward end of a carrier similar to that disclosed in the U. S. patent to Gouldbourn, and comprising a pair of horizontally arranged arms 21 supported by a pair of vertically 50 arranged yokes 23 and 25. As in the machine of the U. S. patent to Gouldbourn, the yoke 23 is adjustable about a fixed shaft 27, and the yoke 25 is adjustable about the shaft 19, an adjustment 55 of these yokes acting to vary the angular position of the horn with relation to the external work support 1. The yokes and carrier are locked in adjusted position by means of a clamping handle 11 screw threaded upon the outer end of the 60 shaft 19.

The machine provided with a horn constructed and arranged in this manner has been found, in practice, to give admirable results in sewing suitcases of certain kinds and other relatively large 70 articles. To adapt the machine for sewing together the parts of cases which have but small mouths, particularly cases such as camera cases and music cases which are relatively deep and relatively narrow from front to rear, the illustrated machine is also provided with means for 75

supporting an alternative arrangement of horn which can be used with advantage when it is desired to use the machine for sewing together parts of relatively narrow and deep cases. For supporting this alternative arrangement of horn, 5 the illustrated machine is provided with a bracket 13, the forward end portion of which is bifurcated and pivotally mounted on the pins 7. Rearwardly of its forward end the bracket 13 is provided with a depending web 15 having in it a slot 17 through which the shaft 19, on which the clamping handle 11 is mounted, passes. The bracket 13 is thus supported at its forward end by the pins 7 on the carrier arms 21 and is supported at its rear end by the shaft 19. The portion of 10 the yoke 25 surrounding the shaft 19 is split, as best shown in Fig. 5, and the web 15 on the bracket 13 is received between the split portions so that an actuation of the clamping handle 11 serves to clamp the yoke 25 and the web 15 15 in fixed position against one of the upstanding ears 29 of the machine frame through which the shaft 19 passes and between which the yoke 25 and web 15 are located. By reason of the slotted engagement of the web 15 with the shaft 25 19, a movement of the yokes 23 and 25 to adjust the position of the horn carrier arms 21 produces a corresponding adjustment of the bracket 13.

The alternative arrangement of the horn is 20 arranged to be supported by the bracket 13 and comprises a somewhat tubular casting 31, forming a housing for a sleeve 33 supporting a horn spindle 35. The casting 31 is arranged to extend 25 upwardly and rearwardly at such an angle and at such a heightwise position in the machine, that the axis of the horn spindle 35 lies substantially parallel to the forwardly and downwardly extending face 37 of the external work-support (i. e., the axis extends upwardly and rearwardly 30 at an angle of some forty-five degrees to the horizontal) and extends a short distance, e. g., one half of an inch, above that surface when positioned to operate on work of an average thickness.

In order to support the casting 31 in this position, and allow it to be actuated to move the work engaging portion of the horn towards and from the external work support during each 35 stitch formation, the bracket has a pair of rods 39 and 41 passing laterally between flanges depending from its left and right hand sides. A yoke 43 is freely mounted on the rod 39 and its lower ends embrace the opposite sides of the casting 31 and are connected to it by pins 45 arranged 40 parallel to the rod 39. A second yoke is mounted on the rod 41 and has an arm 47 depending from it which is connected by a pin 49 to ears extending from the forward side of the casting 31. The yoke 43 and the arm 47 are equal in length but 45 are not quite parallel to each other, the arm 47 being slightly more nearly vertical so that, when the arm 47 is rocked about the rod 41 through a small angle by means hereinafter described, the result will be to cause the work-engaging portion 50 of the horn supported by the horn spindle 35 to move in an arc substantially concentric about the pins 7, i. e., the said work-engaging portion of the horn will move about substantially the same axis 55 as the horn 3.

The sleeve 33 is appreciably smaller in diameter than the bore in the casting 31 and is supported within the latter by two co-axial pins 51 threaded in the sleeve and extending forwardly and rearwardly of the machine perpendicularly to the 70 75

axis of the sleeve. The outer ends of the pins are freely rotatable within the casting and the sleeve is therefore free to swing laterally of the machine about their axes. The horn spindle 35 is secured against endwise movement within the sleeve 33 but is free to rotate therein, ball bearings being provided at the opposite ends of the sleeve to facilitate the rotary movement of the spindle. At its upper end the spindle carries a head 53 through which is formed a bore extending at right angles to the axis of the spindle. The rear end of the horn proper, which latter is indicated at 55, enters into this bore and is clamped in it by clamping screws which pass through split portions of the head. From its rear end the horn is first bowed upwardly to clear adjacent parts of the machine and is then inclined forwardly and downwardly and finally is turned rearwardly and downwardly to provide a work-entering portion 57 lying at right angles to the axis of the horn spindle 35 and therefore substantially parallel to the upwardly and forwardly extending face 59 of the work-support. The horn is formed of a metal tube strengthened against bending by webs 61, 63 welded on the horn. In order to prevent the weight of the horn from causing it to fall idly towards either side of the machine about the axis of the spindle 35, the head of the spindle has a rearwardly projecting lug 65 on it through which a pin 66 extends, to which is connected the upper end of a cable 67 which passes over an idler pulley 69, mounted in a lug secured to the machine frame and has a balance weight 71 connected to its lower end.

The work-entering portion 57 of the horn lies forwardly of the upwardly and forwardly extending face 59 of the work-support and its lower end is flattened (it being conveniently some half an inch in width) and has projecting through it a short stud 73, the axis of which is co-axial with that of the horn-carrying spindle 35. A substantially cylindrical roll 75 some five eighths of an inch in diameter so as just to extend beyond the end and sides of the flattened end of the horn, is freely rotatable on the stud 73 and its peripheral face is arranged to press one of the parts being sewn together against the downwardly and forwardly extending face 37 of the external support while the rear end face of the roll is arranged to press the other part of the work against the forwardly and upwardly extending face 59 of the work-support, the angle between the peripheral face of the roll and its rear end face being bevelled off to facilitate the passage of the needle 71 and the awl 79 through the work without obstruction by the roll.

Like the machine disclosed in the U. S. patent to Gouldbourn above referred to, the machine of the present illustrative embodiment has a cam-actuated lever 84, a rod 83, a bell crank lever 85 and a rod 87 and spring 89 interconnecting the lever 85 with an arm 5 on the block 4 for urging the horn 3 firmly against the work 60 during each cycle of the machine and for relieving the pressure of the horn on the work when the awl is acting to feed the work. This mechanism is made use of in the present illustrative machine for moving the casting 31 in 65 such a manner that the roll 75 will move towards the work somewhat to press firmly on it when desired and will move away from it somewhat at the desired time to relieve its pressure against the work in a path substantially 70 the same as it would follow if it were mounted 75

directly to rock about the pins 7. For this purpose the yoke carrying the arm 47 carries a second arm 91 lying by the side of the arm 47 and a rod 93 connects the arm 91 with the arm 5, the lower end of the rod lying within a slot formed in the arm 5 and being connected to the latter by a readily removable pin 95. The arm 5 will be given slight rocking movements about the pins 7, during the operation of the machine, through its connections with the lever 81, and the arm 5 will therefore impart slight rocking movements to the arm 47 about the rod 41 and will thus cause the casting 31 and the horn 55 supported thereby to move in such a path, controlled by the arms 43, 47, that the roll 75 will move along a path substantially concentric about the pins 7 and will thus apply increased pressure evenly to or relieve the pressure evenly from both parts of the work engaging the faces 37, 59 of the work support.

By supporting the horn 55 in the casting 31 and mounting the latter on the arms 43, 47, the nature of the movement imparted to the roll 75 approximates to that it would have if the casting 31 were mounted to pivot about the pins 7, 25 but the extent of the bodily movement of the casting 31 necessary to impart a given movement to the roll 75 is much smaller with the present arrangement. Further the weight of parts to be moved is less, with the present illustrative construction, than would be likely to be the case if the casting were carried by an arm pivoted to rock on the pins 7. This is particularly so since the balance weight 71 hereinbefore referred to is arranged and connected to the 35 horn bearing in such a manner that the movements of the latter do not bring about equal movements of the balance weight. These facts facilitate the actuation of the horn 55 by the cam-actuated lever 81 and the spring 89 and 40 obviate what might otherwise be a marked tendency, due to the fact that this horn extends so far rearwardly of the sewing point from the roll 75 to the spindle 35, for the horn to be somewhat sluggish in action.

Means is provided whereby the roll 75 may be adjusted in position towards or away from the face 37 of the external support to take care of work in which the part of the work engaging that face differs in thickness from that engaging the face 59. This means comprises a threaded stud 97, having a knurled head on its forward end, which extends rearwardly through the bracket 13 and the rear end of which abuts against a face provided on the rod 41 by cutting into it, as shown particularly in Figure 4. The rod 41 has an eccentric portion between its ends on which portion the yoke carrying the arms 47, 91 is mounted. A compression spring 99 bears against a second face provided on the stud more or less diametrically from the fact previously mentioned and this spring urges the rod in a counterclockwise direction to maintain the first mentioned face in contact with the end of the stud 97. By rotating the stud in appropriate direction, the rod 41 may be rotated in a clockwise direction, as seen from the right, and will thus cause the arm 47 to move downwardly somewhat. This will result in the casting 31 pivoting somewhat about the pins 45 and therefore will result in the roll 75 moving downwardly towards the face 37 of the work support 1. By rotating the stud 97 in the reverse direction, the spring 99 will cause the arm 47 to rise somewhat and thus cause the roll to rise away from the face 37 of the work sup-

- port. To facilitate the accurate positioning of the rear end of the horn within the head 53, there is threaded axially into this end of the horn, which has a sleeve fixed to it, a stop screw 101 which is adapted, when the horn has been inserted into the head, the correct distance, to abut against the pin 66 aforementioned and thus to prevent the horn from being pushed further into the head.
- 5 10 The pin 95 which couples the arm 5 to the rod 93 is, as before stated, a readily removable pin, it being a push pin adapted to be inserted through holes in the slotted portion of the arm 5 and in the lower end of the rod 93. When it is desired 15 to use the horn 3, for example when it is desired to offer relatively large cases to the machine, instead of the horn 55, the latter may be withdrawn from the head 53 and the pin 95 pulled out of the holes in the arm 5 and the rod 93, 20 the horn 3 being then assembled on the machine. Removal of the pin 95 disconnects the casting 31 from the cam actuated lever 81 and in order then to prevent idle movement of the casting 31 during operation of the machine, the 25 yoke carrying the arms 47 and 91 carries a third arm 103 to the lower end of which is coupled the forward end of a tension spring 105, the rear end of which is fixed to the bracket 13. The spring 103 therefore acts to hold the casting 31 30 in an upward position which is determined by contact between the lower end of a set screw 107 threaded downwardly through the bracket 13 and a fourth arm 109 carried by the yoke last mentioned.
- 35 35 Like the machine disclosed in the U. S. patent to Gouldbourn above referred to, the machine of the present illustrative embodiment is provided with a treadle for swinging the horn forwardly to facilitate the introduction on to and removal 40 of work from the horn and external work support 1. For this purpose the arm 5 is connected by a link 111 to an arm 113 pivotally mounted at its rear end on the machine frame. The upper end of a toggle link 115 is pivotally connected to 45 an ear depending from the arm 113 and the lower end of this link is pivoted to the upper end of a second toggle link 117, the lower end of which is mounted in a fixed pivot. The upper link 115 has a rearwardly extending ear to which is connected, conveniently by a pin passing through a 50 hole of slightly larger diameter, the upper end of a treadle rod 119. A relatively long tension spring 121 is connected at its forward end to the point of connection between the toggle links 115, 55 117 and at its rear end to the machine frame and thus tends to straighten the links and lift the arm 113 to maintain the roll 75 pressing against the work, a stop on the treadle rod being preferably provided to limit this action of the spring.
- 60 60 A downward pull on the treadle rod effected through a treadle on its lower end will cause the toggles to break forwardly against the action of the spring 121 and thus to rock the arm 5 downwardly and to withdraw from the work whichever of the two horns may be in use at any time. The toggle connection between the treadle rod and the arm 113 ensures that the horn may be 65 65 swung away from the work without it being necessary for the operator to exercise any severe effort in depressing the treadle.
- 70 70 Similarly to the external work support described in the U. S. patent to Gouldbourn above referred to, the external work support 1 of the present illustrative machine is pivotally mounted on vertically adjustable brackets 123 and the work 75 support and the brackets are coupled, through a heightwise adjustable rod 125 and vertically adjustable sleeves 127 carrying the bracket 123, to the forward yoke 23 of the two which carry the arms 21 by which the horn 3 is supported 5 so that, as these yokes are swung forwardly or rearwardly to cause the horn to cant upwardly or downwardly, the external support is automatically and simultaneously canted, as more particularly described in the patent above mentioned, to a like extent in the same direction to maintain the work-engaging faces of the horn and work-support always in the same relation to each other so that the work will be supported between them with equal efficiency at whatever 15 angle it is presented to the needle and awl for the sewing operation. From a consideration of the Gouldbourn patent, it will be appreciated that the horn and external support both cant, during their adjustment, about a virtual pivot 20 situated on the lower face of the lower frusto conical work engaging roll carried by the horn 3. The slot 17 in the web 15 of the bracket 13 is formed concentrically about this virtual pivot and since the bracket is pivoted on the pins 7 25 at its forward end, angular adjustment in the positions of the yokes 23 and 25 will cause the bracket to move bodily in an arc concentric about the virtual pivot and, since the external work support will simultaneously be canted about 30 the same pivot, the roll 75 on the horn 55 and the two faces of the external support will maintain their relation during the angular adjustment imparted to them through the yokes 23, 25.
- 35 From what has been said above, it will be understood that the present illustrative machine has a horn arrangement similar, in its mounting, construction and in its operation and coupling to the external support, to that described in U. S. patent to Gouldbourn above referred to, 40 and further that the horn 3 of this horn arrangement is readily detachable from the machine (leaving its operating mechanism and coupling to the external support intact) and that the carrier for this horn supports a horn bearing 31 45 for an alternative horn 55, the work-entering portion of which, when looked at from the side of the machine, extends substantially parallel to the forwardly and upwardly sloping face 59 of the work-support and the axis of the spindle 50 55 about which the horn 55 is swung from side to side during the sewing operation lying substantially parallel to the forwardly and downwardly extending face 37 of the work-support. It will further be understood that the axis of the roll 55 75 lies on the axis of the spindle 35 so that, as the horn is swung from side to side about the latter axis, the roll will have no bodily movement relatively to the work.
- When the horn 55 has been assembled in the 60 machine and assuming that a case, indicated at X in Figure 1, having a relatively deep body and a relatively small mouth is to be sewn by the machine, the horn will be swung to the left about the axis of its spindle 35 into such a position that 65 its work-entering portion 57 extends purely widthwise of the machine, it then also lying, by reason of the fact that this portion lies perpendicularly to the axis of the spindle 35, purely horizontally. The operator then depresses the treadle 70 connected to the horn to draw the horn forwardly somewhat to allow the parts of the case to be placed on the work-support after which he releases the treadle and the horn is then urged rearwardly under the action of the springs 89 75.

and 121 to press the two parts of the work against the two faces of the support. The machine is then started into operation and the sewing proceeds along one side corner of the case towards the closed bottom. As the sewing proceeds along this corner, the case will be fed to the left over the horn and the fact that the work-entering portion of the latter extends at this time both purely horizontally and to the left from the roll 75 (i. e. parallel to the line of feed of work through the machine) allows even a very narrow case to be fed easily along it without danger of the parts of the work being obstructed by the horn. When the sewing has proceeded along the side of the case and has reached the end, the operator proceeds to turn the case upwardly on its end towards the position indicated in Figure 1, to allow the sewing to proceed therearound and, as the case is so turned, the work-entering portion of the horn will be carried round with the case, remaining as it does so substantially parallel to the upwardly and forwardly sloping face of the work-support and therefore to the part of the work lying against this face. Therefore, as the case is so turned, the work-entering portion of the horn will have little, or no, bodily forward or rearward movement within the case and will not, therefore, be likely to strike against the forward or rearward parts of the case nor obstruct the continued movement of the work in any way. As the case and horn are so turned in company the roll 75 on the horn will remain in firm pressing engagement with the two parts of the work.

As the sewing proceeds around the end corner, the operator continues to swing the case until its open mouth faces towards the right and, as he does so, the horn will swing in company with it. When the sewing actually commences along the second side corner towards the open mouth, the case will have been turned through 180 degrees from its initial position and the horn will likewise have been turned through the same angle and its work-entering portion then extends horizontally towards the right from its work-engaging roll. The sewing along this second side corner can, therefore, be carried out up to the mouth of the case, the case being meanwhile fed off the work-entering portion of the horn, without the horn obstructing this movement by fouling any part of the work.

As in the case in the horn arrangement described in the U. S. patent to Gouldbourn above referred to, the horn 55 is supported in a pendulous manner about the pins 51 on which its supporting sleeve 33 is pivoted so that the work-engaging portion of the horn may be urged along the line of feed, towards the left or right, out of its normal position to enable a stitch to be sewn in the work close to an upstanding end wall of the work lying at the right or left hand side of the horn. In order to maintain the roll 75 on the horn normally in a constant position to which it is carried by the action on it of the moving work, the tubular casting 31 has extending horizontally through it, at its right-hand side and near its upper end, i. e., above the pins 51 a threaded sleeve in which is housed a spring-pressed plunger 129 which is adapted to bear against the right-hand side of the sleeve 33. By forcing an upstanding wall of the work at the right-hand side of the horn against the work-engaging roll 75 the latter can be moved towards the left along the line of feed, against the action of the spring-pressed plunger, to al-

low this wall to approach closer to the needle plane for the purpose indicated. In order to limit movement of the work-engaging roll in the opposite direction, an adjustable screw is threaded through the left-hand side of the casting 31 to abut against the left-hand side of the latter when the roll has been swung to its limit towards the right of the machine.

The nature and scope of the invention having been indicated, and a machine embodying the several features of the invention having been specifically described, what is claimed is:

1. A machine for sewing suitcases or like articles having, in combination, a work support having angularly disposed surfaces to engage the work externally, stitch forming devices including a needle arranged to move across the corner formed by said surfaces, and a work entering horn provided at its inner end with an internal work support and mounted to rotate about an axis substantially parallel to one surface of the external work support and passing through the work engaging end of the horn.

2. A machine for sewing suitcases or like articles having, in combination, a work support having angularly disposed surfaces to engage the work externally, stitch forming devices including a needle arranged to move across the corner formed by said surfaces, and a work entering horn provided at its inner end with an internal work support, the work entering portion of said horn being substantially parallel to one surface of the external work support, and said horn being mounted to rotate about an axis substantially parallel to the other surface of the external work support and passing through the work engaging end of the horn.

3. A machine for sewing suitcases or like articles having, in combination, a work support having angularly disposed surfaces to engage the work externally, stitch forming devices including a needle arranged to move across the corner formed by said surfaces, a work entering horn mounted to rotate about an axis substantially parallel to one surface of the external work support and passing through the work engaging end of the horn, and a work supporting roll mounted upon the inner end of the horn with its axis in line with the axis of the horn.

4. A machine for sewing suitcases or like articles having, in combination, a work support having surfaces to engage the work externally, disposed at substantially right angles with relation to each other, stitch forming devices including a needle arranged to move across the corner formed by said surfaces, and a work entering horn provided at its inner end with an internal work support, said horn being mounted to rotate about an axis substantially parallel to one surface of the external work support and passing through the work engaging end of the horn, and the work entering portion of said horn being arranged substantially at right angles to the axis of the horn.

5. A machine for sewing suitcases or like articles having, in combination, a work support having angularly disposed surfaces to engage the work externally, stitch-forming devices including a needle arranged to move across the corner formed by said surfaces, a work entering horn provided at its inner end with an internal work support, means comprising a carrier for supporting the horn to rotate about an axis substantially parallel to one surface of the external work support and passing through the work engaging end of the horn, and means supporting the carrier.

permitting an adjustment of the carrier with the horn about an axis parallel to the line of feed and in proximity to the sewing point.

6. A machine for sewing suitcases or like articles having, in combination, a work support having angularly disposed surfaces to engage the work externally, stitch-forming devices including a needle arranged to move across the corner formed by said surfaces, a work entering horn 10 provided at its inner end with an internal work support, means comprising a carrier for supporting the horn to rotate about an axis substantially parallel to one surface of the external work support and passing through the work engaging 15 end of the horn, and means for moving the horn towards and from the external work support during each stitch forming cycle.

7. A machine for sewing suitcases or like articles having, in combination, a work support 20 having angularly disposed surfaces to engage the work externally, stitch forming devices including a needle arranged to move across the corner formed by said surfaces, a work entering horn

mounted to rotate about an axis substantially parallel to one surface of the external work support and passing through the work engaging end of the horn, and means supporting the horn permitting a bodily movement of the internal 5 work support in the line of feed.

8. A machine for sewing suitcases or like articles having, in combination, a work support having angularly disposed surfaces to engage the work externally, stitch forming devices including 10 a needle arranged to move across the corner formed by said surfaces, a work entering horn mounted to rotate about an axis substantially parallel to one surface of the external work support and passing through the work engaging end 15 of the horn, and connections between the horn and the external work support for causing a simultaneous angular adjustment of the horn and work support about substantially the same axis extending parallel to the line of feed in prox- 20 imity to the sewing point.

JOSEPH GOULDBOURN.
